THEODORE WIEDEMANN AND JOSEPH H. TEMPLIN, OF PHILADELPHIA, PENNSYLVANIA, ASSIGNORS, BY MESNE ASSIGNMENTS, TO SANTO MANUFACTURING COMPANY, OF PHILADELPHIA, PENNSYLVANIA, A CORPORATION OF DELAWARE.

AIR-PUMP FOR VACUUM-CLEANERS.

1,170,203.

Specification of Letters Patent.

Patented Feb. 1, 1916.

Application filed June 12, 1909. Serial No. 501,701.

To all whom it may concern:

Be it known that we, THEODORE WIEDEMANN and JOSEPH H. TEMPLIN, both citizens of the United States, residing in the city and county of Philadelphia, State of Pennsylvania, have invented a new and useful Air-Pump for Vacuum-Cleaners, of which the following is a specification.

Our present invention relates to air pumps especially adapted for use in conjunction with the well known vacuum cleaners and consists broadly of a novel construction of an air pump in which the suction creating member of the pumping mechanism is provided with a connecting rod, one end of which is fastened thereto in such a manner that no joint will be formed at such point while the other end of the connecting rod is mounted directly on the crank of the motor, and in the present embodiment, for the purpose of illustration the movable member of the suction creating device is shown as comprising a diaphragm although of course a piston may be employed if desired.

In the suction creating devices or pump mechanisms heretofore employed in this art it has been deemed impracticable to form a direct connection between the motor and the movable member of the suction creating device, especially in cases where a standard electric motor is employed, and in so far as we are aware, we are the first in the art to employ in a pumping mechanism a suction member directly connected to a high speed motor or a diaphragm having its outer periphery rigidly supported and a connecting rod secured thereto the other end of which is mounted on the crank of the motor. We have found, however, by numerous experiments that if the connecting rod is rigidly fastened to the diaphragm or suction member and the other end of the rod mounted on the crank of a motor that a standard electric motor may be employed which runs at a very high speed, in practice between 1200 and 3500 revolutions per minute, so that a strong suction or vacuum can be produced with a machine of very light weight, thereby enabling us to produce a vacuum cleaning apparatus of maximum power and minimum weight so that the entire machine may be readily transported from one place to another by a single person.

To the above ends our present invention 55 consists in its broad scope of a pumping mechanism including a suction creating member having a rod fastened rigidly thereto the other end of the rod being mounted on the crank of a high speed motor and the 60 suction creating member coöperating with a pulsation chamber provided with valve controlled inlet and outlet ports.

Our invention further consists of a novel construction of a casing which is made up 65 of sections so that one section may be readily removed for the purpose of inspection or repairs, the casing being adapted to entirely surround the pumping mechanism and the motor, said pumping mechanism discharging 70 in the present instance directly into the casing, which latter is provided with an exhaust port to the atmosphere whereby a pressure chamber is formed in which the motor is located so that the motor is prop- 75 erly cooled at all times.

Our invention further consists of a novel construction of a pump casing provided with valve controlled inlet and outlet ports and on which the suction creating member 80 of the pump is mounted in a novel manner.

Our invention further consists of a novel manner of mounting the motor so that the same is suitably supported directly above the pump.

It further consists of a novel construction of a pumping mechanism having inlet and outlet ports and a novel construction of valve mechanism coöperating with said ports.

It further consists of other novel features of construction, all as will be hereinafter fully set forth.

For the purpose of illustrating our invention we have shown in the accompanying 95 drawings one form thereof since this embodiment has been found in actual practice to give satisfactory and reliable results, although it is to be understood that the various instrumentalities of which our invention 110 consists can be variously arranged and organized and our invention is not limited to the precise arrangement and organization of these instrumentalities as herein set forth.

Figure 1 represents a perspective view of 105 an air pump for vacuum cleaners embodying our invention, the cover being shown in open position and a portion thereof being

broken away. Fig. 2 represents a sectional view of our device. Fig. 3 represents a sectional view of the suction creating device, certain portions thereof being removed for 5 the sake of clearness of illustration. Fig. 4 represents a plan view of the valve mechanism employed.

Similar numerals of reference indicate 10 corresponding parts in the figures.

Referring to the drawings in the present 15 instance we have shown the casing as comprising a bottom section 1 and a top section 2 which are suitably pivoted together by means of the hinges 3 or equivalent means, the cover being provided with suitable lugs 4 with which the clasps 5 carried by the base portion 1 engage to secure the parts in assembled position.

The base portion 1 is preferably provided 20 with a drawer 6 removably mounted therein it being noted that the clasps 5 are carried by the drawer 6 so that when the parts are in assembled position there will be no leakage of air at the joints formed by such parts.

7 designates an air inlet leading to the observation glass 8 which discharges into the chamber 9 the latter forming a vacuum or filtering compartment. The inlet 7 is adapted to be connected with a suitable hose to 30 which the cleaning nozzle is attached, so that the condition of the air entering the machine through the suction nozzle may be readily observed by the operator as the dust laden air passes through the observation 35 glass 8.

10 designates an apertured plate mounted on the base 1 above which is supported any desired number of layers of dust separating fabric 11. The top 12 of the base 1 forms a 40 support for the pumping mechanism and the motor, and is provided with a port 13 which communicates with a chamber 14 within the pump casing 15. The pump casing 15 is provided with inlet ports 16 controlled by a valve 17, the construction of 45 which will be best understood by reference to Fig. 4. This valve consists in the present instance of a semi-circular disk of leather, rubber or other suitable material which is 50 supported at its inner end by means of a plate 18 provided with suitable fastening devices 19, it being noted that extending outwardly from beneath the plate are the spring fingers 20 which engage the valve 17 and 55 maintain the same normally in closed position.

The valve ports are located in a plate 21 which is seated in a recess in the pump casing 15 and removably secured in position by 60 means of suitable fastening devices 22, it being seen that a packing strip 23 is provided in order that an air tight joint will be made between the plate 21 and the pump casing 15.

65 The casing 15 is provided with a laterally

extending partitioning member 24 which divides the pump casing into two compartments forming the inlet chamber 14 and the exhaust chamber 25. The plate 21 is also provided with the outlet ports 26 which are controlled by a valve 27 similar in construction to the valve 17 and also provided in a similar manner with springs 28 which normally tend to maintain the valve in its closed position. The upper portion of the casing 75 15 is preferably depressed or deflected, as indicated at 29, and between this deflected portion and the diaphragm 30 is located the pulsation chamber 31. The diaphragm 30 has its outer periphery extending beneath 80 the ring 32, suitable fastening devices 33 being provided which pass through the ring 32, the outer periphery of the diaphragm 30 and into engagement with the top of the pump casing 15, thereby rigidly supporting 85 the outer periphery of the diaphragm.

The pump casing is preferably cored out or recessed as indicated at 34 in order to render the same as light as practicable.

35 designates a connecting rod the inner 90 end of which is preferably provided with an enlarged head or plate 36 preferably of thin material or apertured and which is secured in any suitable manner to the diaphragm 30, in the present instance, the washer 37 being 95 provided which is secured to the diaphragm 30 and the head 36 of the rod 35 by means of suitable fastening devices 38, as will be readily apparent by reference to Fig. 3. The outer end of the connecting rod 35 forms a 100 split collar in which the crank pin 39 is adapted to be seated, said pin having preferably mounted thereon a roller bearing 40, seated in the collar of the connecting rod and secured thereto by means of a screw 41 105 or equivalent fastening device. The crank pin 39 is mounted on the crank 42 which latter also carries a balance wheel 43 the same being connected to the shaft of the 110 motor 44 in any suitable manner.

In order to support the motor 44 the pump casing 15 is provided with standards 45 and standards 46 which latter pass through the ring 32, the diaphragm 30 and the pump casing 15, it being noted that a suitable bar 47 is provided which is adapted to be seated on the standards 46 whereby by the employment of suitable nuts 48 the motor is rigidly supported above the pumping mechanism. The pump base 1 is provided 115 with any desired number of discharge ports 49 which open into the casing 2 preferably beneath the motor 44 so that the latter will be properly cooled by the exhaust air passing therearound. The exhaust air passing 120 into the casing 2 exhausts therefrom through the main exhaust port 50.

51 designates a conductor which is adapted to be secured to an ordinary lamp socket the same passing to the motor 44 in 130

the usual manner and the casing 29 is provided with a suitable switch for controlling the motor 44.

The operation of our novel construction 5 will now be readily understood and is as follows: The inlet 7 being first connected with the suction hose the switch is actuated thereby starting the motor 44, whereupon the connecting rod 36 will be reciprocated 10 and owing to the manner in which this rod is fixed to the diaphragm the inner end of the rod in proximity to the diaphragm will be given a combined oscillatory and reciprocatory movement. As the diaphragm is 15 drawn upwardly the parts will assume the position indicated in Fig. 3 and the dust laden air will be drawn through the inlet 7 and the observation glass 8 into the filtering compartment 9. The air then passes 20 through the apertured plate 10 and the filtering fabric 11 so that all foreign matter such as dirt, dust and other impurities are removed from the air and retained in the chamber 9 of the drawer 6 which latter may 25 be readily removed when it is desired to empty the same. The purified air next passes into the chamber 14 through the inlet 13 in the top 12 of the base 1 thence through the inlet ports 16 into the pulsation chamber 30 31, it being understood that the valve 17 is now in the position indicated in Fig. 3, the construction being such that a clearance chamber of considerable area relative to the short, rapid stroke of the diaphragm is provided, as will be understood from said Fig. 35. On the downward movement of the diaphragm 30 the valve 17 will be closed and the valve 27 will open against the tension of the springs 28, whereupon the air in the pulsation chamber 31 will pass therethrough 40 through the ports 26 into the chamber 25 in the pump casing 15, thence through the ports 49 into the pressure chamber 53 in which the motor is located, and therefrom through 45 the main exhaust port 50 to the atmosphere.

When it is desired to employ the pump for blowing purposes the hose is connected with the exhaust outlet 50 as will be apparent to those skilled in this art.

50 Special attention is directed to the novel manner in which the diaphragm is directly connected with the shaft of the motor, since no pivot or hinge connection is employed but in lieu thereof we employ a direct connection one end of such rod being mounted on the crank of the motor while the other end thereof is fastened directly to the diaphragm and since the outer periphery of the diaphragm is rigidly supported and cooperates with the valve controlled ports leading to the pulsation chamber we are 55 enabled by our construction to produce highly advantageous and reliable results.

By employing a light motor of high speed, 60 an air pump for vacuum cleaners may be so

constructed that the entire cleaning device is of very little weight and can be readily transported from one place to another and although in the present instance we have shown the base of the device as being provided with suitable rollers it will be apparent that these if desired may be dispensed with in practice. 70

While in the present instance we have shown the outer casing as having an 75 elongated form it is to be understood that a casing having any desired contour may be employed and still be within the scope of our invention.

It will now be apparent that we have devised a novel and useful construction which embodies the features of advantage enumerated as desirable in the statement of the invention and the above description and while we have in the present instance shown 80 and described a preferred embodiment thereof which has been found in practice to give satisfactory and reliable results, it is to be understood that the same is susceptible of modification in various particulars without departing from the spirit or scope of our invention or sacrificing any of its advantages. 85

Having thus described our invention what we claim as new and desire to secure by Letters Patent, is:— 90

1. In a vacuum pump, a vacuum chamber into which the fluid is initially conducted, a pulsation chamber having an inlet thereto from said vacuum chamber, pumping mechanism coöperating with said pulsation chamber and comprising a flexible diaphragm having its outer periphery suitably supported, means for retaining said outer periphery in position, a connecting rod having one end 100 non-pivotal secured to said diaphragm whereby the latter receives a combined oscillatory and reciprocatory movement within a portion only of said pumping chamber, whereby a relatively large clearance space 105 is provided, a pressure chamber, into which the purified air is discharged, an electric motor in said pressure chamber, a crank operated by said motor, and a direct connection from said crank to said connecting rod 110 for actuating the latter.

2. In a vacuum pump, a vacuum chamber into which the fluid is initially conducted, a pulsation chamber having a valved inlet thereto from said vacuum chamber, pumping mechanism coöperating with said pulsation chamber, and comprising a flexible diaphragm having its outer periphery suitably supported, means for retaining said outer periphery in position, a connecting 120 rod, having one end non-pivotal secured to said diaphragm, whereby the latter receives a combined oscillatory and reciprocatory movement within a portion only of 125 said pumping chamber, whereby a relatively 130

large clearance space is provided, a pressure chamber having a valved outlet thereto from said pulsation chamber, said pressure chamber having a restricted outlet therefrom, whereby a requisite body of compressed fluid is retained in said pressure chamber during the reciprocations of said motor, an electric motor, and connections from said motor to said connecting rod for actuating the latter.

3. In a pumping apparatus, a vacuum reservoir provided with a restricted inlet port whereby the apparatus may be used as a suction device, a pressure reservoir provided with a restricted outlet port whereby the apparatus may be used as a blower, a pulsation chamber intermediate said reservoirs and ports, pumping mechanism co-operating with said pulsation chamber and comprising a flexible diaphragm having its outer periphery suitably supported, means for maintaining said outer periphery in position, an electric motor in one of said reservoirs, a connecting rod having one end secured to said diaphragm, whereby the latter receives a combined oscillatory and reciprocatory movement within a portion only of said pumping chamber, whereby a relatively large clearance space is provided, a crank

operated by said motor, and a connection 30 from said crank to said connecting rod for actuating the latter.

4. In a pumping apparatus, a vacuum reservoir, having a restricted inlet port, a pressure reservoir having a restricted outlet 35 port whereby the apparatus can be used as a blower, a pulsation chamber intermediate said reservoirs, pumping mechanism co-operating with said pulsation chamber and comprising a flexible diaphragm having its 40 outer periphery suitably supported, means for maintaining said outer periphery in position, a connecting rod having one end non-pivotedly secured to said diaphragm, whereby the latter receives a combined oscillatory 45 and reciprocatory movement within a portion only of said pumping chamber, whereby a relatively large clearance space is provided, an electric motor located within one of said reservoirs, and a direct connection 50 from said motor to said connecting rod for actuating the same.
